SHEET COLLECTING AND FOLDING MECH- ANISM FOR PRINTING PRESSES

Howard M. Barber, Pawcatuck, Conn., assignor to
C. B. Cottrell & Sons Company, Westerly, R. I.,
a corporation of Delaware

Application April 13, 1933, Serial No. 665,922

18 Claims. (Cl. 270—13)

The object of this invention is to provide novel means whereby selected products of a different number of pages and page widths may be delivered in one direction or in opposite directions, as desired.

The object of this invention is more particularly to provide a novel means whereby the product of a web printing press, when the product is cut into an odd number of sheets or superimposed sheets, may be collected in full or in part on a combined collecting and folding cylinder having an even number of collecting surfaces, folded off therefrom, and delivered to one delivery in four page signatures or multiples thereof; the remaining sheet or sheets, if any, being taken by a combined transfer and folding cylinder, folded off therefrom, and delivered to another delivery.

A practical embodiment of my invention is represented in the accompanying drawings, in which:

Fig. 1 represents a diagrammatic side elevation showing one of the couples of a rotary web perfecting printing press in connection with which my improved sheet collecting and folding mechanism is used;

Fig. 2 represents a diagrammatic side elevation of my improved sheet collecting and folding mechanism;

Fig. 3 represents a detail view in side elevation illustrating the cams for controlling the sheet engaging and folding devices on the several cylinders; and

Fig. 4 represents a detail view in side elevation illustrating another form of cam used for silencing one of the combined collecting and folding cylinder cams and for silencing the sheet taking devices on the combined transfer and folding cylinder.

In the embodiment herein shown, the web is designed to be printed and perfected in a single color on each cycle of the press, forty-eight pages, six pages around and four pages across. In Fig. 1, one of the printing couples is shown, the form or printing cylinder being denoted by A and the impression cylinder by A'.

The printed web four pages wide may be fed from the press to the coating web feed rolls 1 and 2 around the roll B. Two narrow webs two pages wide may be fed from the press to the feed rolls 1 and 2 around the rolls B and C respectively. Four narrow webs one page wide may be fed from the press to the feed rolls 1 and 2 around the rolls B, C, D and E respectively.

Two coating rotary cutters 3 and 4 are arranged in position to receive the web or webs from

the feed rolls 1 and 2 and cut the same into an odd number of sheets or superimposed sheets each cycle of the press. The rotary cutter 3 is provided with two diametrically opposed cutting blades 5 and 6 and the rotary cutter 4 is provided with two diametrically opposed cutting blades 7 and 8 arranged to coact with their corresponding cutting blades 5 and 6 respectively, on the rotary cutter 3. These rotary cutters are two-thirds the circumference of the printing cylinder A, or four pages around. In other words, these coacting rotary cutters cut sheets equal in length to one-third the circumference of the printing cylinder, or two pages around. A combined sheet collecting and folding cylinder 9 has its coacting folding and delivery cylinder denoted by 10. The cylinder 9 is provided with two diametrically opposed sets of sheet engaging devices which are herein shown as sets of normally projecting disappearing sheet impaling pins 11 and 12 respectively. This collecting and folding cylinder 9 is further provided with two diametrically opposed folding blades 13 and 14. The folding and delivery cylinder 10 is provided with a single set of folding jaws 15 arranged to coact at the proper times with the folding blades 13 and 14 of the collecting and folding cylinder 9, after the selected product has been collected on said cylinder 9.

The combined collecting and folding cylinder 9 is two-thirds the circumference of the printing cylinder, or four pages around. The folding and delivery cylinder 10 has a circumference equal to that of the printing cylinder, or six pages around. Therefore, the cylinder 9 rotates one and one-half revolutions to each revolution of the cylinder 10.

A suitable delivery 17 is provided for receiving the signatures from the folding and delivery cylinder 10.

A combined sheet transfer and folding cylinder 18 is arranged to coact at the proper times with its companion folding and delivery cylinder 19. The combined transfer and folding cylinder 18 is provided with a single set of sheet engaging devices, in the present instance a set of normally projecting disappearing impaling pins 20. This cylinder 18 is also provided with a single folding blade 21. The folding and delivery cylinder 19 is provided with a single set of folding jaws 22 arranged to coact at the proper times with the folding blade 21 on the cylinder 18.

A suitable delivery 24 is provided for receiving the signatures from the folding and delivery cylinder 19.

The means which I have shown for controlling the operation of the several sheet engaging and folding devices for collecting, folding and delivering the selective product to one or both deliveries 5 may be constructed, arranged and operated as follows:

A changeable rotary box cam is mounted on the shaft 25 of the combined transfer and folding cylinder 18, which box cam comprises a common 10 half member 26 and two interchangeable half members 27 and 28. The common half member 26 has a semicircular cam groove 29 concentric with the shaft 25. The interchangeable half member 27 has a semicircular groove 30 matching 15 with the groove 29, said semicircular groove 30 having an offset portion 31. The interchangeable half member 28 is provided with a semicircular groove 32 matching with the groove 29 in the common half member 26.

When it is desired to control the action of the sets of normally projecting pins on the collecting and folding cylinder 9 at their sheet taking point, the rotary cam members 26 and 27 are used. A movable cam 33 is brought into and out of its position to engage the studs or rollers 34, 35 of 20 the sets of disappearing pins 11 and 12 by providing the movable cam 33 with a stud or roller 36 which travels in the cam groove 29, 30. When it is not desired to control the action of the sets of 25 disappearing pins 11 and 12 at their sheet taking point the cam members 26 and 28 are used and the cam 33 is held out of its operative position as its stud or roller 36 travels in the cam groove 30, 32.

A movable cam 37 controls the sets of disappearing pins 11 and 12 on the cylinder 9 to permit the signatures to be folded off onto the folding and delivery cylinder 10, which movable cam 37 is provided with a stud or roller 38 traveling in the groove 39 of a rotary box cam 40 mounted on the shaft 41 of the said cylinder 10, 35 said groove 39 having an offset portion 42.

A stationary cam 43 is arranged in position to engage the stud or roller 44 of the folding jaws 45 15 on the cylinder 10 to open the jaws at the proper point to deliver the signatures to the delivery 17 and to hold the said jaws open until they reach the point where they receive the signatures from the cylinder 9.

A stationary cam 45 is arranged in position to engage the stud or roller 46 of the set of 50 disappearing pins 20 on the transfer and folding cylinder 18 to permit the sheets to be folded off onto the folding and delivery cylinder 19. This 55 stud or roller 46 may be held in an inoperative position when so desired, as for instance by means of a removable pin 47 engaging the spring pressed rod 48 beyond its guide 49, after the stud or roller 46 has been moved inwardly to a point where it will not engage the cam 45.

A fixed cam 50 is arranged in position to engage the stud or roller 51 of the folding jaws 22 on the folding and delivery cylinder 19 to open the folding jaws at the proper point to deliver the signatures onto the delivery 24 and to hold the jaws open until they receive the sheets from the cylinder 18.

In the embodiment of the invention shown and described herein, the operation is as follows:

The full forty-eight page product of the press is collected, folded, and delivered in any of the following combinations, to-wit:

Four eight page signatures to delivery 17 and four four page signatures to delivery 24; or four 70 twelve page signatures to delivery 17; or two

sixteen page signatures to delivery 17 and two eight page signatures to delivery 24; or two twenty-four page signatures to delivery 17; or one thirty-two page signature to delivery 17 and one sixteen page signature to delivery 24.

When the full web four pages wide is to be collected, folded, and delivered, the cutters 3 and 4 80 cut the web into three sheets each cycle of the press. When the web is slit into two narrow webs two pages wide, the two webs are combined and fed to the rotary cutters 3, 4, where they are cut into three pairs of sheets each cycle of the press. When the web is slit into four narrow webs one page wide, the four narrow webs are combined and fed to the cutters 3 and 4 where 85 they are cut into three groups of four sheets each, each cycle of the press.

When four eight page signatures are to be delivered to the delivery 17 and four four page 90 signatures to delivery 24, the web four pages wide is passed through the rotary cutters 3 and 4. The first and third sheets are taken by the pins 11 on the cylinder 9 and the second sheet by the pins 20 on the cylinder 18. The two superimposed sheets on the cylinder 9 are folded off 95 on to the delivery cylinder 10 and there slit longitudinally by the slitters 16 into four eight page signatures and then deposited on to the delivery 17. The second sheet is folded off from the cylinder 18 on the delivery cylinder 19 and there 100 slit longitudinally by the slitters 23 into four four page signatures and then deposited on to the delivery 24.

Where four twelve page signatures are to be delivered to the delivery 17, the web four pages wide is passed through the rotary cutters 3 and 4. The so cut sheets are collected alternately by the pins 11 and 12 on the cylinder 9 until each 110 set of pins has three sheets. These so collected sheets are folded off on to the delivery cylinder 115 10 and there slit into four signatures of twelve 10 page each and then deposited on to the delivery 17.

Where two sixteen page signatures are to be delivered to delivery 17 and two eight page signatures to delivery 24, the web is slit longitudinally into two narrow webs two pages wide and superimposed before passing through the rotary 120 cutters 3 and 4. The first and third groups of sheets are taken by the pins 11 on the cylinder 125 9 and the second group of sheets is taken by the pins 20 on the cylinder 18. The four superimposed sheets on cylinder 9 are folded off on to the delivery cylinder 10 and there slit longitudinally by the slitters 16 into two sixteen page signatures 130 and then deposited on to the delivery 17. The second group of sheets is folded off from the cylinder 18 on the delivery cylinder 19 and there slit longitudinally by the slitters 23 into two eight 135 page signatures and then deposited on to the delivery 24.

Where two twenty-four page signatures are to be delivered to the delivery 17, the web is slit longitudinally into two narrow webs two pages wide and superimposed before passing through the 140 rotary cutters 3 and 4. These groups of sheets are then taken alternately by the pins 11 and 12 on the cylinder 9 until three collections are made on each pin. The sheets are then successively folded off on to the delivery cylinder 10 and slit 145 longitudinally by the slitters 16 into two twenty-four page signatures and then deposited on to the delivery 17.

Where one thirty-two page signature is to be delivered to delivery 17 and one sixteen page sig- 150

nature to delivery 24, the web is slit longitudinally into four narrow webs one page wide and superimposed before passing through the rotary cutters 3 and 4. The first and third groups of sheets are collected by the pins 11 on the cylinder 9 and the second group of sheets is taken by the pins 20 on the cylinder 18. These groups of sheets are folded off on to their cylinders 10 and 19 and the signatures deposited by said cylinders on to the 10 deliveries 17 and 24 respectively.

Where one forty-eight page signature is to be delivered to delivery 17, the web is slit longitudinally into four narrow webs one page wide and superimposed before passing through the rotary cutters 3 and 4. These groups of sheets are taken alternately by the pins 11 and 12 on the cylinder 9 until three collections are made on each set of pins. These groups of sheets are then successively folded off on to the delivery cylinder 10 and deposited thereby on to the delivery 17.

It is to be understood that when a part of the product is to be delivered to both of the deliveries 17 and 24, the cam 33 is brought into its operative position by the required intervals, by the use of the half cam member 27, to cause certain of the sheets to be taken by the transfer cylinder 13.

It will also be understood that where the whole product is to be delivered to the delivery 17, the movable cam 33 is held out of its operative position by using the half cam member 28. In this latter instance the stud or roller 46 for the impaling pins 20 is secured in the position in which it will not be engaged by the fixed cam 45.

It will also be understood that, if so desired, the 35 collected and folded signatures other than those one page wide may be slit longitudinally on the folding and delivery cylinder 10 by one or more slitters 16 and on the folding and delivery cylinder 19 by one or more slitters 23.

40 It is evident that various changes may be resorted to in the construction, form and arrangement of the several parts without departing from the spirit and scope of my invention, and hence I do not intend to be limited to the particular 45 embodiment herein shown and described, but

What I claim is:

1. Coacting rotary cutters arranged to cut the web product of one cycle of a printing press into an odd number of sheets or groups of sheets, and 50 coacting collecting and folding cylinders arranged to receive the so cut sheets or groups of sheets from the cutters and to collect and fold the sheets or groups of sheets into various paged signatures, and deliver them.

55 2. Coacting rotary cutters arranged to cut the web product of one cycle of a printing press into three sheets or groups of sheets, and coacting collecting and folding cylinders arranged to receive the so cut sheets or groups of sheets from 60 the cutters and to collect and fold the sheets or groups of sheets into various paged signatures, and deliver them.

65 3. Means for cutting the web product of one cycle of a printing press into an odd number of sheets or groups of sheets, and means for collecting and folding the sheets or groups of sheets into various paged signatures and delivering them, including a collecting and folding cylinder 70 having an even number of collecting surfaces.

75 4. Means for cutting the web product of one cycle of a printing press into three sheets or groups of sheets, and means for collecting and folding the sheets or groups of sheets into various paged signatures and delivering them, in-

cluding a collecting and folding cylinder having two collecting surfaces.

5. Means for cutting the web product of one cycle of a printing press into an odd number of sheets or groups of sheets, and means for collecting and folding the sheets or groups of sheets into various paged signatures and delivering them, including a collecting and folding cylinder having an even number of collecting surfaces and a coacting folding and delivery cylinder.

6. Means for cutting the web product of one cycle of a printing press into three sheets or groups of sheets, and means for collecting and folding the sheets or groups of sheets into various paged signatures and delivering them, including a collecting and folding cylinder having two collecting surfaces and a coacting folding and delivery cylinder.

7. Means for cutting the web product of one cycle of a printing press into an odd number of sheets or groups of sheets, and means for collecting and folding the sheets or groups of sheets into various paged signatures and delivering them, including a collecting and folding cylinder having an even number of collecting surfaces and a coacting folding and delivery cylinder, the collecting and folding cylinder being two-thirds the circumference of the folding and delivery cylinder, and the folding and delivery cylinder being the same circumference as the printing cylinder of the printing press.

8. Means for cutting the web product of one cycle of a printing press into three sheets or groups of sheets, and means for collecting and folding the sheets or groups of sheets into various paged signatures and delivering them, including a collecting and folding cylinder having two collecting surfaces and a coacting folding and delivery cylinder, the collecting and folding cylinder being two-thirds the circumference of the folding and delivery cylinder, and the folding and delivery cylinder being the same circumference as the printing cylinder of the printing press.

9. Coacting rotary cutters arranged to cut the web product of one cycle of the printing press into an odd number of sheets or groups of sheets, and coacting collecting and folding cylinders arranged to receive the sheets or groups of sheets from the cutters and to collect and fold the sheets or groups of sheets into various paged signatures, and deliver them to one or two delivery points.

10. Coacting rotary cutters arranged to cut the web product of one cycle of a printing press into three sheets or groups of sheets, and coacting collecting and folding cylinders arranged to receive the sheets or groups of sheets from the cutters and to collect and fold the sheets or groups of sheets into various paged signatures, and deliver them to one or two delivery points.

11. Means for cutting the web product of one cycle of a printing press into an odd number of sheets or groups of sheets, and means for collecting and folding the sheets or groups of sheets into various paged signatures and delivering them to one or two delivery points, said last named means including a collecting and folding cylinder having an even number of collecting surfaces, a transfer and folding cylinder, and two folding and delivery cylinders coacting with the collecting and folding cylinder and the transfer and folding cylinder respectively.

12. Means for cutting the web product of one cycle of a printing press into three sheets or

- groups of sheets, and means for collecting and folding the sheets or groups of sheets into various paged signatures and delivering them to one or two delivery points, said last named means including a collecting and folding cylinder having two collecting surfaces, a transfer and folding cylinder, and two folding and delivery cylinders coacting with the collecting and folding cylinder and the transfer and folding cylinder respectively. 10
13. Means for cutting the web product of one cycle of a printing press into an odd number of sheets or groups of sheets, and means for collecting and folding the sheets or groups of sheets into various paged signatures and delivering them to one or two delivery points, said last named means including a collecting and folding cylinder having an even number of collecting surfaces, a transfer and folding cylinder, and two folding and delivery cylinders coacting with the collecting and folding cylinder and the transfer and folding cylinder respectively, the collecting and folding cylinder being two-thirds the circumference of the remaining cylinders. 15
14. Means for cutting the web product of one cycle of a printing press into three sheets or groups of sheets, and means for collecting and folding the sheets or groups of sheets into various paged signatures and delivering them to one or two delivery points, said last named means including a collecting and folding cylinder having two collecting surfaces, a transfer and folding cylinder, and two folding and delivery cylinders coacting with the collecting and folding cylinder and the transfer and folding cylinder respectively, the collecting and folding cylinder being two-thirds the circumference of the remaining cylinders. 20
15. Coacting rotary cutters arranged to cut the full width web product of one cycle of the press into three sheets, or a half width product into three groups of two sheets each, or a quarter width product into three groups of four sheets each, and coacting collecting and folding cylinders arranged to receive the sheets or groups of sheets from the cutters and to collect and fold the sheets or groups of sheets into various paged signatures, and deliver them. 25
16. Coacting rotary cutters arranged to cut the full width web product of one cycle of the press into three sheets, or a half width product into three groups of two sheets each, or a quarter width product into three groups of four sheets each, and coacting collecting and folding cylinders arranged to receive the sheets or groups of sheets from the cutters and to collect and fold the sheets or groups of sheets into various paged signatures, and deliver them to one or two delivery points. 30
17. Coacting rotary cutters arranged to cut the full width web product of a press of forty-eight pages, six pages around and four pages across, in each cycle of the press, into three sheets four pages wide and two page long, or three groups of two sheets each, two pages wide and two pages long, or three groups of four sheets each, one page wide and two pages long, and coacting collecting and folding cylinders arranged to receive the sheets or groups of sheets from the cutters and to collect and fold the sheets or groups of sheets into various paged signatures, and deliver them. 35
18. Coacting rotary cutters arranged to cut the full width web product of a press of forty-eight pages, six pages around and four pages across, in each cycle of the press, into three sheets four pages wide and two pages long, or three groups of two sheets each, two pages wide and two pages long, or three groups of four sheets each, one page wide and two pages long, and coacting collecting and folding cylinders arranged to receive the sheets or groups of sheets from the cutters and to collect and fold the sheets or groups of sheets into various paged signatures, and deliver them to one or two delivery points. 40
